UNITED STATES PATENT OFFICE.

ISRAEL C. GELLMAN, OF CHICAGO, ILLINOIS.

WRENCH.

Application filed August 5, 1921. Serial No. 490,036.

To all whom it may concern:

Be it known that I, ISRAEL C. GELLMAN, a citizen of the United States, residing at Chicago, in the county of Cook and State of Illinois, have invented certain new and useful Improvements in Wrenches, of which the following is a specification, reference being had to the accompanying drawings, and to the reference characters marked thereon, which form a part of this specification.

This invention relates to improvements in adjustable wrenches. The invention consists in the devices and combination of devices herein illustrated, described and more particularly pointed out in the appended claims.

In the drawings,—

Fig. 1 is a top plan view of a wrench embodying my invention; a portion being broken away and sectioned to disclose interior parts otherwise covered.

Fig. 2 illustrates in a side or edge view, the same wrench with a modified form of locking device.

Fig. 3 is a top plan view of the wrench illustrated in Fig. 2.

Fig. 4 is a transverse, vertical, sectional view, taken in the plane of the dotted line 4—4 of Fig. 3, and looking in the direction indicated by the arrows.

Fig. 5 is a vertical sectional view taken in the plane of the dotted line 5—5 of Fig. 1, looking in the direction indicated by the arrows.

The wrench is provided with a handle or shank member A, preferably of relatively thin metal, and of any desired length, and preferably tapered from its jaw end to its narrow, movable end. It is provided with a jaw member B and with an upwardly extending lug C. A movable member D is provided with a laterally extending jaw E and is pivotally and adjustably secured to the wrench A by means of a bolt F.

The edge of the shank or handle member A is provided with a flat surface 1, a second surface 2 extending at right angles to the surface 1, and a surface 3 at an oblique angle to the surface 1, the surface 3 extending from the surface 2 to the nut engaging surface 4 of the jaw B.

The upturned member C is provided with a longitudinally disposed slot 5, the walls of which form a suitable guide-way for the bolt F, which passes through the member D and the slot 5. The rear edge of the up-

turned lug C joins the adjacent edge of the wall or shank member A with a strengthening fillet or curved rib 6. The edge of the jaw member E is provided with a jaw surface 7 which in all operative positions of the wrench will be parallel with the jaw surface 4 of the jaw B. The movable member D has an edge surface 8 which extends angularly from the surface 7 and parallel with a surface 9 on the jaw B. From the lower edge of the surface 8 the edge of the movable member D is provided with a plurality of ratchet teeth 10. The bolt F may be secured by a washer 11 and by riveting so as to hold the movable member D in operative position upon the gripping end of the wrench in all positions when the member D is moved longitudinally of its length and the bolt F up and down in the slot 5. The teeth 10 of the member D are adapted for operative engagement with similar teeth formed on the face or edge of a tempered steel block G, which is riveted at 12 to the shank member A; the edge of the jaw B being cut away at 13 and 14 to form two surfaces against which the rear surface of the insert block G will bear.

While this is the preferred construction on account of facility in the manufacture of the teeth 15, which are adapted to engage with the ratchet teeth 10, it will be manifest that the insert block G may be made integral with the jaw B, this doing away with the shoulders and engaging surfaces 13 and 14, and with the rivet 12.

The under surface of the movable member D is cored out to leave a hollow space indicated at *d*, primarily to enclose a spring S and surround a stop or abutting shoulder *a*. The spring S is provided with a bent end 16 adapted to be inserted in a curved recess 17 in one wall of the cored out chamber *d*. The free end of the spring S rests upon one face of the lug or shoulder *a* which latter is integral with the member A. The bearing surface of the lug *a* is parallel with the inside wall of the member D as clearly shown in Fig. 1. The shape of the engaging end 16, of the spring S and of the curved recess 17 are such that the spring must be inserted in the recess "on edge" and will therefore be held firmly in position to move longitudinally of the lug *a* as the arm D is moved.

The thickness of the jaws B and E during the entire length of the bearing surfaces 4

and 7 are the same, as clearly indicated in Fig. 2, while the other parts of the movable member D, and the lug C and member A are of lesser thickness, as indicated in the various figures. I prefer to provide the lower end of the movable member D with a finger hold 18, whereby the operator may grasp the member D and swing it about the bolt F so that the jaws E and F may be moved out of parallel relation and the teeth 10 and 15 be disengaged. In such position, tension will be put upon the spring S against the shoulder α , but the member D may nevertheless move longitudinally of its length for adjustment purposes, the bolt F sliding longitudinally in the slot 5 of the lug C.

Immediately upon releasing the hand hold 18, the tension of the spring S will bring the teeth 10 and 15 into engagement, so that a hexagonal bolt will be grasped and held on four of its sides by contact with the surfaces 7, 8, 3 and 4.

When a bolt is thus held by the jaws B and E, pressure exerted on the handle or shank A will permit of the proper turning of the bolt or nut in the desired direction. When the wrench is thus being turned, it will be clear that the pressure against the face 7 will extend through the lug E and against that thickened portion thereof which bears against the shoulder 1 of the lug C, and will be exerted in the other direction against the block G so that the toothed surfaces 10, 15, will be solidly clamped together. There will be no danger of the gripping jaws loosening their hold upon the bolt head or nut.

In the modification shown in Figs. 2, 3 and 4, I have omitted the spring S and the shoulder α as a means of holding the teeth 10, 15, in operative engagement, and in lieu thereof, I have provided a locking wedge lever L, pivotally secured by a bolt or rivet 19 to the arm or shank member A. The cam member L is provided with an eccentric 20 which by turning the member L, bears against the back edge or surface 21 of the movable member D. When the position of the member D is to be shifted, the locking lever L will be moved into the position shown in dotted lines in Fig. 3, and when the eccentric or wedge edge thereof is brought into operative position against the edge 21 of the member D, the lever L will be as shown in full lines in Figs. 2 and 3, thus locking the teeth 10, 15, in operative engagement.

If, for example, the parts are in the position shown in dotted lines in Fig. 3, and the wrench be placed over a nut or bolt so that two of the faces of the latter bear against the surfaces 3, 4, and the surfaces 7, 8 contact in any manner with said bolt or nut, a turning pressure on the handle or shank member A will promptly cause the movable

member D to swing about the bolt or pivot F until the teeth 10, 15, engage, and then the lever L may be swung about its pivotal rivet 19 to lock the parts together.

It will be observed that in both forms of the invention herein illustrated, I have provided thickness of metal and strength where same are required and have made the parts thin and light where the work to be performed does not produce severe strain.

The wrench is designed to be made by drop forging and will be case hardened where necessary.

The gripping surfaces 4 and 7 of the jaws B and E are shown straight to lay firm hold upon parallel sides of a nut or bolt head, but, manifestly, these surfaces may be made roughened or curved to equally lay hold of a pipe or cylindrical bolt or rod, and I would have it so understood without additional illustration of such familiar feature.

The wrench is of simple construction, exceedingly efficient, has no complicated parts to get out of order and manifestly is readily adjustable to any sized nut or bolt, within the limits of its size.

I claim as my invention:

1. An adjustable wrench comprising a shank provided at one end with a fixed jaw member and a relatively thin slotted lug, the longitudinal axis of the slot and the forward marginal face of the lug being at right angles to the gripping face of said fixed jaw member, a jaw member movably secured to the slotted lug and provided with a relatively thin movable member integral therewith, complementary engaging surfaces on the fixed jaw and on the edge of the movable member, means for bringing said surfaces into interlocking engagement, and means for securing the two thin members together while permitting relative movement between them.

2. The adjustable wrench described, comprising a shank provided at one end with an integral jaw member, an integral relatively thin slotted lug, and a fixed lug, combined with a second jaw member, a relatively thin movable member integral with the said second jaw member, a plurality of inter-engaging teeth on the fixed jaw and on the edge of the relatively thin movable member, a bearing lug on the shank, a spring bearing at one end upon said movable member and at its other end upon said bearing lug to normally bring the teeth on the fixed jaw and the said movable member into interlocking engagement, and means for securing the two thin members together while permitting relative movement between them.

3. The adjustable wrench described comprising a shank provided at one end with a fixed jaw member and an integral relatively thin slotted lug, combined with a movable

jaw member integral with a relatively thin movable member, a plurality of inter-engaging teeth on the fixed jaw and the edge of the movable member, a bearing lug on the shank, a spring having one end fixed to the movable member and the other adapted to bear upon said fixed lug to normally bring the teeth into interlocking engagement, and means for securing the two thin members together while permitting relative movement between them, comprising a pivot stud secured to the movable member and adapted to travel in the slotted lug.

4. The adjustable wrench described comprising a shank provided at one end with an integral or fixed jaw member and with a relatively thin slotted lug, a relatively thin movable member mounted upon the slotted lug by means affording relative movement of said member upon the lugs, a movable jaw member integral with said movable member provided with two shoulder surfaces, one adapted to contact with the edge of the slotted lug and the other with the edge of the movable jaw, interlocking engaging means on the edge of the movable member and the fixed jaw, cooperating means on the shank and the movable member for normally bringing the said engaging means in interlocked relation and means for locking said engaging means in the interlocked position.

5. The adjustable wrench described comprising a shank provided at one end with an integral or fixed jaw member and with a relatively thin slotted lug, a relatively thin movable member mounted upon the slotted lug by means affording relative movement of said member upon the lugs, a movable jaw member integral with said movable member provided with two shoulder surfaces, one adapted to contact with the edge of the slotted lug and the other with the edge of the movable jaw, interlocking engaging means on the edge of the movable member and the fixed jaw, cooperating means on the shank and the movable member for normally bringing the said engaging means in interlocked relation and means for locking said engaging means in the interlocked position, said interlocking means including a plurality of teeth on the movable member and on the fixed jaw.

6. In a wrench, a relatively wide and thin shank member provided with an angularly disposed slotted lug extending from one

edge, a fixed jaw member of greater thickness projecting from the shank end near its other edge, and an integral elongated rib on one face extending in a direction parallel with the median line of the slotted lug, the gripping face of the fixed jaw being normal to the rib, in combination with an elongated, relatively thin, movable member pivotally mounted upon the shank and slotted lug to swing about the pivotal connection and to be moved bodily, lengthwise of the lug, a jaw integral with said movable member and of the same thickness as the fixed jaw, inter-engaging surfaces between the edge of said movable member and the fixed jaw, there being a recess in the inner face of the movable member adapted to receive the rim, and a flat metal spring positioned therein on edge and secured at one end to a wall of the recess, its free end having bearing engagement with the rim.

7. In a wrench, a relatively wide and thin shank member provided with an angularly disposed slotted lug extending from one edge, a fixed jaw member of greater thickness projecting from the shank end near its other edge, and an integral elongated rib on one face extending in a direction parallel with the median line of the slotted lug, the gripping face of the fixed jaw being normal to the rib, in combination with an elongated, relatively thin, movable member pivotally mounted upon the shank and slotted lug to swing about the pivotal connection and to be moved bodily, lengthwise of the lug, a jaw integral with said movable member and of the same thickness as the fixed jaw, inter-engaging surfaces between the edge of said movable member and the fixed jaw, there being a recess in the inner face of the movable member adapted to receive the rib, a flat metal spring positioned therein on edge and secured at one end to a wall of the recess, its free end having bearing engagement with the rib, and a metal insert in the fixed jaw shaped on one edge to form a part of said interengaging surfaces.

In testimony that I claim the foregoing as my invention I affix my signature, in the presence of two witnesses, this 3rd day of August, 1921.

ISRAEL C. GELLMAN.
